UNITED STATES PATENT OFFICE

120,640

DESIGN FOR A GAUGE CASE OR SIMILAR ARTICLE

Carl H. Graesser and Frank H. Hopkins, Bridgeport, Conn., assignors to Manning Maxwell & Moore, Incorporated, New York, N. Y., a corporation of New Jersey

Application March 12, 1940, Serial No. 90,855

Term of patent 14 years

To all whom it may concern:

Be it known that we, Carl H. Graesser and Frank H. Hopkins, citizens of the United States of America, residing at Bridgeport, in the county of Fairfield and State of Connecticut, have invented a new, original, and ornamental Design for a Gauge Case or Similar Article, of which the following is a specification, reference being had to the accompanying drawing, forming a part thereof.

In the drawing,

Fig. 1 is a front view of a gauge case embodying our new design, and

Fig. 2 is a side view thereof.

We claim:

The ornamental design for a gauge case or similar article, substantially as shown.

CARL H. GRAESSER.
FRANK H. HOPKINS.
